UNITED STATES PATENT OFFICE.

LORETTO CORY, OF SHELBYVILLE, INDIANA.

WATER-PROOF GARMENT.

SPECIFICATION forming part of Letters Patent No. 316,245, dated April 21, 1885.

Application filed July 29, 1884. (No model.)

To all whom it may concern:

Be it known that I, LORETTO CORY, a citizen of the United States, residing at Shelbyville, in the county of Shelby and State of Indiana, have invented certain new and useful Improvements in Water-Proof Garments; and I do hereby declare that the following is a full, clear, and exact description of the same, reference being had to the annexed drawings, 5 making a part of this specification, and to the letters and figures of reference marked thereon.

The present invention has for its object to 25 provide a water-proof garment for ladies' wear, consisting of a combined skirt, skirt-protector, and cape with hood and detachable sleeves, constructed substantially as shown in the drawings, and hereinafter described and 30 claimed.

In the accompanying drawings, A represents the skirt open in the front and fastened by buttons or other suitable means. The skirt 35 A around its interior, near the bottom, is provided with a band, a, having suitable button-holes for fastening thereto the protector B, which is composed of any suitable cloth. The band a, as should be noticed, is stitched to the skirt along its upper edge only, leaving the 40 lower portion of the band free to be fastened to the buttons on the protector B with little trouble.

Any suitable means may be employed for 45 fastening the protector to the band of the skirt—such as hooks and eyes—so long as it will admit of the protector being readily disconnected therefrom.

The protector B is long enough to be folded up at the bottom beneath the dress and other skirts, and is decreased in fullness by being 50 gathered onto a smaller band, b, which is fastened by means of buttons or hooks to a band, c, provided with holes or rings and suspended by a series of tapes, d, from a band, e, fastened around the waist beneath the dress and 55 other petticoats.

By means of the above-described garment an envelope is formed wherein the dress and 60 petticoats are inclosed, protecting them in bad weather from any mud or moisture.

An important feature in the protector is its fullness, which gives room enough for it to be worn over several skirts without crumpling them in the least, and being drawn into such a small band beneath the petticoats prevents 65 it being cumbersome to the limbs of the wearer. Another feature is that it may be adjusted to any other skirt or the gossamer circulars now in common use by simply sewing a band provided with button-holes or rings on the inner 70 side thereof the required distance from the bottom.

To complete the garment I provide a suitable water-proof cape, C, having the hood D and sleeves E, the latter being detachably connected to the cape by buttons or other fastenings, this acting in connection with the other portions of the garment to make a complete 75 protector to the wearer.

Having now fully described my invention, 80 what I claim as new, and desire to secure by Letters Patent, is—

The herein-described water-proof skirt, consisting of the circular A, provided with a band, a, near its lower end, and the protector B, detachably connected to said band and to a band, c, supported by a series of straps, d, from a 85 waist-band, e.

In testimony that I claim the above I have hereunto subscribed my name in the presence 90 of two witnesses.

LORETTO CORY.
